PHYSIOTHERAPY APPARATUS

Louis A. La Vine, Los Angeles, Calif.

Application March 26, 1951, Serial No. 217,431

2 Claims. (Cl. 128—24.1)

1

My invention relates to the art of healing and particularly that branch commonly designated as physio-therapy. Specifically, the invention relates to that phase of the art of physio-therapy which relies upon such physical phenomena as those resulting from induced oscillatory and electro-magnetic flux effects.

The present application is a continuation-in-part of my earlier application, Serial No. 15,248, filed March 16, 1948, for Method of Physio-Therapy and Apparatus Therefor, and I reserve such earlier date for all common subject matter set forth in said applications and claimed herein.

To further advance the healing art it is among the objects of the invention to provide a new and improved method of physio-therapy which combines the beneficial effects of previously practiced methods and which is productive of results far in excess of any anticipated combination.

Another object of the invention is to provide a new and improved method of physio-therapy wherein the effect of electro-physio-therapy is accentuated many fold by combining therewith induced physical oscillation by vibrational effects.

Another object of the invention is to combine induced physical oscillation of selected magnitude and frequency with magnetic lines of force, forming a magnetic flux electrically induced and confined to a field of said magnetic lines within the beneficial range and wherein those known to be harmful are excluded.

Still another object of the invention is to provide a new and improved combined means of physio-therapy wherein the patient is immersed in a sea or field of electrically induced magnetic flux and while immersed therein is subjected to specific effects induced either electrically or physically, or both, the electrically induced magnetic flux being a combination of both electric and magnetic phenomena.

With these and other objects in view, the invention consists in the novel construction, arrangement and combination of the various parts of an apparatus whereby the objects contemplated are attained, as hereinafter more fully set forth, pointed out in the claims and illustrated in part in the accompanying drawings.

In order to assist in the illustration of the method described herein, certain drawings are shown illustrating one means by which the combined physical oscillation and electrically incited magnetic flux may be produced.

Figure 1 is a side elevational view of the subject supporting the device, partially broken away, showing the location of the blanket of insulated electric wire conductors and vibrator unit.

Figure 2 is a longitudinal sectional view taken on the line 2—2 of Figure 1.

Figure 3 is a fragmentary sectional view show-

2

ing the manner of attachment of certain loops of the blanket conductors to the device.

Figure 4 is a fragmentary cross-sectional view taken on the line 4—4 of Figure 1 showing the attachment of a source of induced physical oscillations.

This invention contemplates utilizing the full effect of an electro-magnetic flux treatment accentuated by simultaneous induced physical oscillations to the person treated. Comparative tests have demonstrated that the effect of a treatment by the combination method exceeds the ordinarily expected aggregate of these two treatments when taken separately by such a large amount that the benefits of the combined effect cannot be disputed.

An important feature of the apparatus is to produce what may be described as a sea or field of electric induction producing a magnetic flux. By this it is meant to create a field substantially greater than the area occupied by the body of the patient to be treated and while the patient is within that field to subject the patient to one or more other treatments in combination. If only a part of the patient is to be treated, obviously the area of the field or sea of magnetic flux effect need not be as great. Conversely, it can readily be understood that on occasions more than one person may be treated simultaneously if the area or sea of electrically produced lines of magnetic flux is made large enough.

One of the principles involved in the invention is to create this over-all area wherein there is produced an electrically induced magnetic flux effect of a certain magnitude and character, and then to combine with that effect some accessory treatment. The accessory treatment which is involved in this invention may be the subjecting of the patient, or some part of him, to an induced physical oscillation of certain selected magnitude and frequency.

Although the physical means of creating and generating the electro-magnetic flux effects above described may vary considerably, there has been set forth, by way of example only, one means of producing the desired combination effect. This means is embodied in the structure illustrated in the drawings.

In the drawings, in this particular instance, a couch 10 is supported by legs 11 upon the floor 12. The couch, in the instance shown, includes side walls 13, 13', ends 14, 14' and a top 15. If preferred the top, as illustrated in the drawing, may be of substantial thickness and include a cushion 16 resting upon a bed panel 17.

To provide a sea or field of electro-magnetic lines of force constituting a magnetic flux of the desired character there is utilized, on this particular occasion, a flat blanket 18 of insulated cop-

per wire attached to the underside of the bed panel 17. As here illustrated, the coil consists of forty-eight loops indicated by the reference character 23 each six feet long which extend around insulated spools 24 on the underside of the bed panel 17, thereby aggregating substantially 288 lineal feet of single strand wire. It has been found that satisfactory treatments are experienced when the 288 feet of insulated wire providing the field is of #27 gauge.

The idea in the arrangement of the loops of the blanket 18 is to extend the area occupied by the wire over practically the entire area of the bed panel so that when electricity flows through the loops the magnetic lines of flux induced thereby will be uniformly spread over a very substantial area within which a patient or subject may be positioned. The loops of the blanket 18 are shown terminating in binding posts 20 and 21 which are connected to a trunk line 22 supplied from a suitable source of alternating current.

Inasmuch as the blanket 18 is composed of nothing other than 288 feet of #27 insulated copper wire, ordinarily termed magnet wire, it may provide insufficient resistance for the alternating current supply.

In order that sufficient resistance may be present, there can be added in series with the blanket 18 a small compact coil 19 containing a suitable footage of a satisfactory resistance wire which will absorb a sufficient portion of the alternating current supply to prevent the loops of the blanket 18 from overheating. A successful resistance coil may be one made of 288 feet of #27 gauge copper insulated wire, being wire of the same gauge and character as that of the blanket 18. The selection of gauge of the wire, the length of the blanket 18 and the electric current used are instrumental in setting up the proper wave length and frequency of the waves in the field.

It should be recalled that it is not the requirement that the loops of the blanket 18 constitute a source of heat but rather a source of electromagnetic lines of force constituting magnetic flux. On the contrary, it is the desire to do away with direct heating by means of heat radiated from hot wires by means of substituting therefor electrically induced magnetic lines of force which, by induction combined with dielectric effect, excite the molecules of the patient immersed in the sea or field of said lines of force.

As indicated particularly in Figure 2, a switch 29 controls the turning on and shutting off of the current through the blanket 18.

Also attached to the couch, and in the example illustrated, to the underside of the bed panel 17 is an oscillator unit 30. In the present example the oscillator unit consists of an electric motor 31 having a shaft 32, the ends of which extend outwardly from the motor casing.

At both ends of the shaft are mounted off-center weights 33 on short arms 34 which extend at right angles to the shaft 32. Upon rotation of the shaft at a conventional motor speed of 1700 R. P. M. the weights set up an air oscillation which induces a physical vibratory effect upon the patient or subject reclining thereupon, the couch remaining substantially stationary throughout the period of oscillation.

Because of the rather large mass and weight of the couch, the activity of the motor 31 will not produce therein what in any substantial sense could be designated as vibration; that is to say, shaking vibrations. The real result is more in

the nature of a vibratory tendency which may be more properly described as an induced oscillatory wave effect or wave pattern. The effect is not in fact a shaking of the subject or patient placed upon the couch, but rather an induced soothing oscillating effect extremely moderate in its magnitude.

Action of the oscillator unit may be controlled by means of a switch 35 conveniently located near the other switches 28 and 29 at the end 14 of the couch.

My invention may be embodied in other specific forms without departing from the spirit or essential characteristics thereof. The present embodiment as above set forth is therefore to be considered in all respects as illustrative and not restrictive, the scope of my invention being indicated by the appended claims rather than by the foregoing description, and all changes which may come within the meaning and range of equivalency of the claims are therefore intended to be embraced therein.

The invention having been herein described, what I claim as new and desire to secure by Letters Patent is:

1. An apparatus for physio-therapy treatments, comprising a supporting device adapted for the support of a subject to be treated, a blanket of insulated electric conductors attached to said supporting device, means for connecting in circuit a source of electric current with the conductors of said blanket and adapted to set up an electrically incited magnetic flux communicable to said subject without producing a substantial change of temperature in said blanket, and a unit for producing mechanically agitated air currents attached to said support adjacent to the area occupied by said blanket, said air currents being communicable to said subject and cooperating with said magnetic flux to act upon and to influence said subject when resting upon said support.

2. An apparatus for physio-therapy treatments for animate objects, comprising a couch for the support of the patient to be treated, a blanket of insulated copper wire attached to and located underneath said couch, means for connecting in circuit a source of alternating electric current with the wires of said blanket and adapted to set up an electrically incited reversing magnetic flux communicable to the patient without producing a substantial rise in temperature in said blanket, and a non-shaking motor unit adapted to produce mechanically agitated air currents attached to said couch adjacent to the area occupied by said blanket and subjecting said patient while resting upon said couch to the influence of said currents.
